UNITED STATES PATENT OFFICE.

ANTON MEHLFELDER, OF NEW YORK, N. Y., ASSIGNEE, BY MESNE ASSIGNMENTS, TO
HERMAN REHER, OF NEW YORK, N. Y.

INTERMITTENT MECHANICAL MOVEMENT.

1,160,928.

Specification of Letters Patent. Patented Nov. 16, 1915.

Application filed April 18, 1914. Serial No. 832,691.

To all whom it may concern:

Be it known that I, ANTON MEHLFELDER, a citizen of the United States, residing at New York city, county and State of New York, have invented certain new and useful Improvements in Intermittent Mechanical Movements, of which the following is a clear, full, and exact description.

This invention relates to a mechanical movement of the intermittent type, that is to say, a device that will transform a rotary movement into an intermittent movement. My improved device for gaining the above result can be applied to any apparatus requiring such a movement, for instance a motion picture apparatus in which the film is advanced step by step by a constantly rotating driving shaft.

The device will be fully set forth in the following specification and claims.

In the drawings: Figure 1 is a sectional face view of an embodiment of my invention, the section being taken on a line 1—1 in Fig. 2. Fig. 2 is a sectional side view, the section being taken on a line 2—2 in Fig. 1, looking in the direction of the arrow. Fig. 3 is a sectional plan view partly in elevation. Figs. 4 and 5 are diagrammatic views illustrating the driving disk and operating means therefor in two positions. Figs. 6 and 7 are diagrammatic side views showing the driven disk, and lock therefor in two positions. Fig. 8 is a perspective view, illustrating one form of universal shaft connection which I can employ.

My invention is herein embodied in an arbitrary form; that is to say the manner of assembling the parts.

As herein illustrated, my invention consists of a driven member 2 and a driving member 4, herein shown as gears, the primary driving or power device, being omitted as well as the element operated by the driven gear.

The object of the device is to operate the gear 2 step by step, or intermittently, the gear shaft 4 carrying the gear 3, being constantly rotated during the operation of the machine. To intermittently operate the gear 2 and its shaft 5 I employ a disk 6 having a face cam 7 designed to operate a vibratory frame 8 pivotally mounted at one end thereof upon the driven shaft 5, the other end being pivotally supported by a stud 9 carried by a trunnion 10 for the frame 11.

The frame 11 rotatably supports the cam disk 6 and is itself pivotally supported upon the trunnion 10 and bearing 12 upon the standard 13. The frame 11 is made in halves 14 and 15 bolted together as at 16 and is therefore clamped to its pivotal supports 10 and 12.

As can be seen in Fig. 2, the cam disk 6 is carried by a shaft 17 pivotally mounted in the casing or framing 11. The shaft 17 also carries a fly-wheel 19 which serves the purpose of any fly-wheel or balance. Adjacent the cam-disk 6 I locate the vibratory frame 8, the axis of which is in line with the axis of the casing 11. The frame 8 carries in this instance two projecting horns or arms 20 and 21. As can be seen in Fig. 1, the arm 20 is provided with a bracket 22, which engages the pin or stud 9, and the arm 21 with a bracket 23 engaging the shaft 5, the bracket 23 being provided with pins or studs 24 adapted to engage openings 25 in the driven disk 26 on the shaft 5. From an inspection of Fig. 1, it will be evident that the frame 8 will swing or oscillate to and fro upon the stud 9 and shaft 5. The rotary path of movement of the pins or studs 24 is in alinement with the openings 25 in the driven disk 26. The function of the disk 6 is to oscillate or vibrate the frame 8 and thus rotate the disk 26 step by step. The step by step movement being accomplished by causing the pins 24 to engage the openings 25 at intervals. The engagement of the pins 24 and openings is brought about by an eccentric 27, on the shaft 17, working in a pocket or yoke opening 28 in the frame 8. The function of the eccentric 27 is to reciprocate the frame 8 and thereby cause the pins 24 to engage the opening 25 in the disk 26, at intervals to be described hereinafter. During the periods of rest of the disk 26 it is locked against vibration by a locking device consisting of a reciprocating frame 27^a working on guides 28^a, the locking device being actuated by an eccentric 29 on the shaft 17. An adjusting gland or bushing 30 is used to adjust the cam 6 relative to the arms 20 and 21 of the vibratory frame 8, a lock nut 31 being used to bind the gland in an adjusted position.

As will be seen in Fig. 1, the eccentrics 27 and 29 are set oppositely in order that the locking device 27^a will engage the disk 26 when the frame 8 is in its retracted position, 110

the cam spot 32^a being set to vibrate the frame as soon as the pins 24 enter the openings 25. By the time the pins 24 enter the openings 25 the end 32 of the locking device will have cleared the disk 26. As illustrated the device has just completed a stroke and is ready to commence another. During the first half revolution of the shafts 4 and 17 the cam 27 will force the slide to the left, but will cause the pins 24 to enter the openings 25 before the completion of the stroke. About the time that the pins 24 enter the openings 25 the rise 32^a of the cam 7 will contact with the arm 20 of the frame 8. By the time that the half revolution has been completed, the pins 24 will have been forced completely into the openings 25 and the rise 32^a of the cam will have rocked the frame 8 to the position shown in Fig. 5 im- parting to the disk 26 one-sixth of a revolution, and hence the gear 2. During the said first half revolution the cam 29 will have moved the locking slide 27 to the right (Fig. 1) withdrawing the lock 32 away from the disk 26. That is to say, by the time the rise 32^a of the cam 7 reaches the arm 20 the lock 32 will have cleared the said disk, but will continue to move to the right until the half revolution is completed. During the second half revolution of the driving shaft the pins 24 will be withdrawn from the openings 25, and the frame 8 rocked back to its normal position as shown in Fig. 4. During a portion of the return stroke of the frame 8, it, the frame, will remain in the position to which it has been rotated by the cam in order that the pins 24 can be withdrawn from the disk 26 without disturbing the position of the said disk, the dead portion 33 of the cam 7 being extensive enough to accomplish this result. By the time that the pins have been withdrawn, the lock 32 will have engaged the disk 26 and locked it; and at about this time, a little later in fact, the rise 32^a of the cam 7 will contact with

the arm 21 of the frame 8 and will rock the said frame back to the normal position. By the time the said cam has completed the revolution, it will be obvious that the frame 8 is normally out of engagement with the driven disk 26, it being in engagement there- with only during the time that the said disk is to be advanced a step. By reason of the pivotal mounting of the frame 11 the said frame can be tilted by means of the handle 35, in order to rotatably advance or retard the driven disk 26. In order to permit the frame 11 to be tilted and yet not interfere with the rotation of the shaft 17 I provide a universal connection 36 consisting of a slot 37 in the end of the shaft 17 and a projection 38 on the shaft 4 adapted to enter said slot.

I claim as my invention:

1. A cam carried by a continuously rotat- 65 ing shaft, an oscillating member bearing upon said cam and actuated thereby, an intermittent shaft adjacent thereto, said intermittent shaft having openings to be engaged by the oscillating member for the purpose of effecting a desired intermittent motion.

2. A device for producing an intermittent movement consisting of a pivotally mounted frame, a driven shaft carried thereby, a cam carried by said shaft, a pivotally mounted 75 slideable frame adjacent said cam and adapted to be rocked thereby, the pivotal points of said frame being disposed in a line at a right angle to the axis of said driving shaft, a rotatable disk adjacent said frame, means to slide said frame to engage said disk at intervals, and means to lock said disk during the periods of rest thereof.

Signed at New York city, New York, this 85
31st day of March 1914.

ANTON MEHLEFELDER.
